DISPLAY CHEST FOR SILVEWARE, ETC.

Robert W. Drummond, Oneida, and Max Rogers,
Earlville, N. Y., assignors to Oneida Limited,
Oneida, N. Y., a corporation of New York

Application August 21, 1935, Serial No. 37,128

1 Claim. (Cl. 206—44)

This invention relates to improvements in chests designed primarily for use with silver and silver plated flatware articles and for use by dealers in the display of such articles to their trade.

5 The object of the present invention is to provide a chest in which such articles may be satisfactorily displayed by the dealer and one in which they and the interior of the chest itself will be protected from the dust of the atmosphere and 10 the articles also be protected from the tarnishing effect of the gaseous elements of the latter.

Generally stated the chest provided by the present invention is one comprising a body portion for containing and displaying some of the 15 articles and also a lid portion for containing and displaying others of the articles, the body and lid portions being hinged together so that they may be opened for such display and each of them provided with a removable transparent cover 20 through which the articles within it may be viewed, these covers, when in place on the body portion or lid, protecting the contents thereof against the dust and tarnishing effect of the atmosphere.

25 In the accompanying drawing—

Figure 1 is a perspective view of the chest opened;

Figure 2 is a vertical section of the same, also opened;

30 Figure 3 is a perspective view of the removable protective cover for the body of the chest;

Figure 4 a fragmentary cross-section of the same, on an enlarged scale, and

Figure 5 a perspective view of the removable 35 protective cover for the lid of the chest.

Referring to said drawing, 1 represents the body and 2 the lid of the chest, the two being hinged at 3 (Fig. 2) and the opening display movement of the lid 2 being limited by a tape 40 connection 4 between it and the body 1 (Fig. 2).

The body 1 is provided interiorly with a rack 5 for receiving the articles to be displayed therein and the lid is provided on its under or inner side with racks 6, 7, for receiving the articles to be displayed therein, such display occurring, of course, only as and when the dealer desires it. At other times the lid is swung down to closing position.

While the chest is open for display its interior and its contents would be exposed to the objective effects of the atmosphere and, as to silver or silverplated articles, to its tarnishing effect, unless protected therefrom. These atmospheric 5 effects, however, are avoided by the present invention by the provision of covers 8, 9, each consisting of a frame in which is set a pane of transparent material 10, 11, respectively, these panes being preferably of non-frangible material such 10 as sheets of cellulose acetate, which is also preferred because of its non-inflammable nature.

These covers are readily removable from the body and lid to provide for convenient access to the contents thereof and the removal of such 15 contents and their replacement by other articles.

A matter of considerable importance, however, is the character of the fit between the covers and the body and lid. This, as shown and as contemplated by the present invention, is a close one, so 20 much so as to prevent the entrance of dust into the body and lid and also the entrance therein of the tarnish-producing gases of the atmosphere, particularly where, as here, the bottoms of the body and lid are lined with soft, yielding mate- 25 rial 12 with which the inner edges of the covers contact in their closed position.

What is claimed is:

A display chest comprising a body and a lid hinged thereto, the lid being a substantial duplicate of the body, the body being formed with a bottom and upstanding side and end walls of considerable depth, a soft, yieldable lining within the body at the bottom thereof and a bodily separable and removable cover for the body, said 30 cover comprising a frame open at its bottom and having side and end walls of considerable depth with a top of transparent, substantially non-frangible and non-readily-inflammable material, the cover fitting within the body and having its sides 35 and ends making close, dust-excluding contact with the sides and ends of the body, with its bottom edges engaging and making close, atmospheric-excluding contact with the soft, yieldable lining of the body.
